Geo. E. Jew

Attorney

UNITED STATES PATENT OFFICE.

HARRY W. WEAVER, OF ALLENTOWN, PENNSYLVANIA.

AIR-FEEDING ATTACHMENT FOR FURNACES.

Application filed February 24, 1922. Serial No. 539,005.

To all whom it may concern:

Be it known that I, HARRY W. WEAVER, a citizen of the United States, residing at Allentown, in the county of Lehigh and 5 State of Pennsylvania, have invented certain new and useful Improvements in Air-Feeding Attachments for Furnaces, of which the following is a specification.

This invention relates to devices adapted 10 for feeding air to a furnace by means of an attachment mounted on the coal door of a furnace or the like, the object being to provide an improved device of this kind for the purpose of mixing the proper amount 15 of air with the gases arising from the bed of fuel in order to produce perfect combustion, as well as to pre-heat the air supplied to the furnace. The construction of 20 the device is such that the air is evenly distributed over the fire bed, whereby combustion is increased, fuel is saved and smoke 25 is prevented as well as the escape of any unconsumed gases arising from the fuel.

The invention is illustrated in the accompanying drawings in which Fig. 1 is a front view of a part of a furnace provided with the invention. Fig. 2 is a plan, partly in section, of the device removed from the furnace door. Fig. 3 is a longitudinal section of the device.

Referring specifically to the drawings, 30 indicates the door casing of a furnace and 6 the door thereof to which the device is attached.

The device comprises a pipe 8 the outer 35 end of which is threaded and fitted through a hole in the door, as shown in Fig. 1, and it is supported in position by nuts 9 respectively engaging the inside and out- 40 side of the door plate, and by adjusting the nuts on the pipe the location of the device with respect to the door can be varied. At its outer end, that is on the outside of the door, the pipe is provided with a funnel 45 10, which may be screwed on the pipe and held by a nut 11, and this funnel acts to direct a flow of air to intake openings 12 formed in the pipe and communicating with the bore thereof. The effective inlet through 50 these openings may be varied by adjusting a screw plug 13 which is tapped into the outer end of the pipe and controls the ports 12 by opening the same more or less as desired.

The pipe 8 projects sufficiently within 55 the furnace to deliver the air well within the fire box, above the fuel bed therein, and said pipe opens at its inner end into a cylindrical super-heating chamber 14 screwed on the end of the pipe and enclosed within 60 an outer cylindrical spraying chamber 15, from which it is spaced, the chamber 15 being conveniently made in halves and clamped on the threaded end of the pipe 8. The inner chamber 14 has a plurality of 65 holes 16 through the same, and the outer chamber 15 has a plurality of holes 17 therein, these holes being directed at various angles, both in the sides and ends of the 70 cylinder, so as to effect a distribution of the air in various directions over the fuel bed.

When the device is mounted on the coal door as indicated the draft will draw in air through the holes 12 and pipe 8 to the inner chamber 14 where the air will be 75 highly heated, and will flow from said chamber through the holes 16 into the space between the cylinders, and thence be discharged through the holes 17 in the outer cylinder over the fuel bed. The heated air 80 thus delivered mixes with the gases arising from the fuel, and being supplied in proper amount will produce a perfect combustion and prevent the waste of gases through the stack or into the house. The air is intensely 85 heated before it is sprayed or distributed over the fire bed and consequently will give effective combustion. The pipe 8 will be long enough to position the distributing head over a hot part of the fuel bed, instead 90 of just inside the door. The discharge holes in the inner chamber are preferably placed in the upper, lower and rear sides thereof, so that the air will have to pass partly around in the space between the cylinders 95 before it is distributed through the outer chamber. In this way effective heating and uniform distribution of the air is accomplished.

The other advantages of the device will be 100 apparent to those skilled in the art and the invention is not limited to the particular embodiment shown and described.

I claim:

An air feeding device for furnace doors 105 comprising an externally threaded pipe extending thru said door, the outer part of the pipe having air inlet openings in the

side walls thereof, a screw plug in the outer end of the pipe, adjustable to open or close said openings, a funnel shaped air collector screwed on the out side of the pipe, between said openings and the door, nuts on the pipe, clamping the same to the door, an outer perforated chamber having screw threaded engagement on the pipe, inside the door, and an inner perforated chamber, also

screwed on the inner end of said pipe, inside of said outer chamber.

In testimony whereof, I affix my signature in presence of two witnesses.

HARRY W. WEAVER.

Witnesses:

EDWIN H. STINE,
MARGARET H. MAGER.
